CLAIM

The ornamental design for a stove, as shown and described.

DESCRIPTION

FIG. 1 is a top plan view of a stove showing my new design;

FIG. 2 is a side elevation view thereof, the opposite side being a mirror image of that shown;

FIG. 3 is a front elevation view thereof; and

FIG. 4 is a rear elevation view thereof.

The broken line showing of environmental structure in FIGS. 1-4 is for illustrative purposes only and forms no part of the claimed design.

FIG. 1

FIG. 2

FIG. 3

FIG. 4
